INTERNATIONAL JUSTIFICATION SIGNAL
FOR MONOTYPE COMPOSING MACHINES

Leo A. Schmitt, Washington, D. C.

Application October 13, 1933, Serial No. 693,503

11 Claims. (Cl. 116—67)

This invention relates to signal-means for use with typesetting machines of that character in which the matter is set up in the form of perforations in a record strip, and which are generally known as monotype composing machines.

In the use of these machines, when the line being set up comprises matter requiring justification or alinement before as well as after the completion of the line, it is customary for the operator to mark the point upon the line-scale where the intermediate justification or alinement is required, in order that he may know when the pointer on the em-rack reaches the point on the line-scale where the intermediate justification or alinement is required. However, since these machines are not equipped with audible signals for apprising the operator that he is nearing a point where intermediate justification or alinement is required, the operator frequently fails to notice the registration of the pointer on the em-rack with the point on the line-scale where the intermediate justification or alinement is required, and when this occurs considerable time and work are necessary to remedy the error and effect the intermediate justification or alinement.

The invention has for one of its objects to prevent the operator from making the mistake of passing an intermediate point on the line-scale where justification or alinement is required, and to attain this end comprehends signal-means adapted to apprise the operator that he is nearing the point where the intermediate justification or alinement is required, the signal-means being adapted to be connected to the line-scale for operation by the pointer on the em-rack immediately before the pointer reaches the point on the line-scale where the intermediate justification or alinement is required.

The invention has for a further object to provide signal-means of the character stated which will not obstruct the operator's view of the line-scale and which will mark or indicate the point on the line-scale where the intermediate justification or alinement is required.

According to the invention, the signal-means comprises a clip having a pointer and adapted to be engaged with the line-scale with the pointer registering with the point on the line-scale where the intermediate justification or alinement is required, a bell carried by the clip, and a bell-hammer on the clip for operation by the pointer on the em-rack immediately before this pointer reaches the point on the line-scale where the intermediate justification or alinement is required.

The invention is hereinafter more fully de-

scribed and claimed, and illustrated in the accompanying drawing, wherein:

Figure 1 is an elevational view of the signal-means applied to the line-scale of a monotype composing machine;

Figure 2 is a view in front elevation of the signal-means detached from the line-scale;

Figure 3 is a view in rear elevation of the signal-means;

Figure 4 is a view in side elevation of the signal-means;

Figure 5 is a sectional view taken on the line 5—5 of Figure 2;

Figure 6 is a sectional view taken on the line 6—6 of Figure 2;

Figure 7 is a detail sectional view on an enlarged scale taken on the line 7—7 of Figure 2, and

Figure 8 is a perspective view of the base of the signal-means.

Although applicable to other forms of monotype composing machines, and to tabulating machines generally, the signal-means is shown for the purpose of illustration as applied to a monotype composing machine of the kind disclosed in Letters Patent 944,405, issued December 28, 1909. Only such parts of this machine are shown as are necessary to illustrate the application and operation of the signal-means.

Referring in detail to the drawing, 1 designates the units-wheel, 2 the em-rack and 3 the line-scale of a monotype composing machine of the kind disclosed in the above identified Letters Patent. The em-rack 2, which is advanced by the units-wheel 1, operates in a guide 4, and is provided with a pointer 5 which moves from left to right over the line-scale 3 as the em-rack advances. The line-scale 3 is mounted in a guard-frame 6 which is secured to the guide 4 and which inclines downwardly and forwardly from the face of the guide.

The signal-means which is adapted to be secured to the line-scale 3, and which is adapted to be operated by the pointer 5, comprises a base 7. This part has its central portion and upper edge cut away, as at 8 and 8^a respectively, to reduce its weight to a minimum. A pintle 9 extending horizontally across the rear side of the base 7 is secured in brackets 10 which may be formed by parts struck up from the base. A post 11 extends forwardly from the lower right-hand corner of the base 7, and a post 12 extends forwardly from the upper left-hand corner of the base. The spindle 9 and the posts 11 and 12 are preferably formed from a single piece of round stock, and

the front ends of the posts are screw threaded. Stops 13 formed integrally with the base 7 extend rearwardly from the base at opposite sides of the vertical center of the base and close to the upper 5 end of the base. A pointer 14 extends upwardly from the upper right-hand corner of the base 7, and a finger-piece 15 extends downwardly from the base.

A bell 16 is mounted upon the post 11. A sleeve 10 17 arranged on the post 11 between the base 7 and the bell spaces the bell from the base. A nut 18 engaged with the post 11 clamps the bell 16 between itself and the sleeve 17. Suitable washers 18^a are interposed between the bell 16, sleeve 17 15 and nut 18. A hammer-lever 19 for the bell 16 is pivoted at its upper end to the post 12, and is provided at its lower end with a head 20. The hammer-lever 19 is spaced from the base 7 by washers 21, and is held on the post 12 by a nut 22. A 20 trip-lever 23 for the hammer-lever 19 is pivoted between its ends to the post 12 in front of the hammer-lever. The lower and shorter arm of the trip-lever 23 is provided with a rearwardly directed lug 24 which contacts with the right-hand side of the hammer-lever 19. The upper and longer arm of the trip-lever 23 extends above the base 7, and is provided at its upper end with a rearwardly directed operating arm 25. The trip-lever 23 is spaced from the hammer-lever 19 25 and the nut 22 by washers 26 and 27. A spring 28 connected at its ends to the sleeve 17 and hammer-lever 19 swings the hammer-lever into contact with the bell 16 when the hammer-lever is tripped. A spring 29 is secured at one end to the base 7, and has its free end bent at right angles, as at 29^a, and arranged between the bell 16 and the hammer-lever 19. The spring 29 constitutes a yielding stop against which the hammer-lever 19 is normally held by the spring 28, 30 to prevent accidental movement of the hammer-lever. The spring 29 is weaker than the spring 28, to permit the latter to swing the hammer-lever into contact with the bell 16 when the hammer-lever is tripped through the medium of the trip-lever 23. A spring 30 is secured at its 35 lower end to the hammer-lever 19, and has its upper or free end bent to provide a hook 30^a which engages the left-hand edge of the trip-lever 23. The spring 30 yieldingly holds the trip-lever 23 in parallel arrangement with relation to the hammer-lever 19. When the trip-lever 23 is in this position, the lug 24 on the trip-lever contacts with the right-hand side of the hammer-lever 19, with the result that when the trip-lever 40 is moved to the right the hammer-lever is swung away from the bell 16 against the tension of the spring 28. When the trip-lever 23 is released, the spring 28 reacts, swinging the hammer-lever 19 into contact with the bell 16. After the bell 16 45 has been sounded, the hammer-lever 19 is held against further movement by the springs 28 and 29. The spring 30 is light, and the edge of the trip-lever 23 with which the spring engages is inclined, to permit the trip-lever 23 to yield readily to the left without imparting any movement to the hammer-lever 19.

A clamp-member 31 located at the rear side of the base 7 is pivotally connected at its lower end to the spindle 9 by a bearing 32, formed by 50 bending said end of the clamp-member into substantially cylindrical form. The bearing 32 is located between the brackets 10, and is held by the brackets against longitudinal movement on the spindle 9. A finger-piece 33 extends downwardly from the lower end of the clamp-member

51, and is located directly in rear of the finger-piece 15. A spring 34 located between the finger-pieces 15 and 33, and held in place by lugs 35 and 36 on the finger-pieces, constantly tends to urge the clamp-member 31 in the direction of the base 7. The clamp-member 31 is narrower than the base 7, and is provided at its upper end with upwardly and laterally directed extensions 31^a. The extensions 31^a cooperate with rubber pads 37 on the rear side of the upper end of the base 7, to 10 secure the signal to the line-scale 3. The extensions 31^a contact with the rear side of the guard-frame 6 for the line-scale 3, and the pads 37 contact with the face of the line-scale. The upper edges of the extensions are beveled to permit them 15 to be readily inserted in the upwardly narrowing space between the guide 4 and frame 6.

In practice, the signal-means is clipped to the line-scale 3 with the pointer 14 of the signal-means registering with the point on the line-scale 20 where an intermediate justification or alinement in the line to be set up is required. The trip-lever 23 is located to the left of this point on the line-scale 3 with its arm 25 in the path of movement of the pointer 5 on the em-rack 2. As the 25 pointer 5 nears this point on the line-scale 3, the pointer will contact with and pass the trip-arm 25, with the result that the hammer-lever 19 will be actuated to sound the bell 16. The actuation of the signal apprises the operator that he is 30 nearing a point on the line-scale where intermediate justification or alinement is required, such point being marked or indicated by the pointer 14 of the signal-means. If justification or alinement is required at two or more points before 35 the completion of the line to be set up, the signal is applied with its pointer 14 registering with the point on the line-scale 3 where the first justification or alinement is required. After this justification or alinement has been made, the signal-means is moved or adjusted on the line-scale 3 to 40 register its pointer 14 with the point on the line-scale where the next justification or alinement is required, and this adjustment of the signal-means is continued until all the intermediate justifications or alinements have been made. Instead of using one signal-means and adjusting it on the line-scale 3 as the intermediate justifications or alinements are made, as 45 many of the signal-means may be used as there are points where intermediate justification or alinement is required, the signal-means being positioned on the line-scale 3 with their respective pointers 14 registering with the respective points on the line-scale where the intermediate justifications or alinements are required.

By grasping the finger-pieces 15 and 33 and moving them in the direction of each other, the signal-means may be readily applied to, adjusted upon or removed from the line-scale. During 60 the application of the signal-means, the lugs 13 contact with the lower edge of the guard-frame 6 for the line-scale 3, to position the signal-means on the line-scale with all portions thereof except the pointer 14 and the trip-lever 23 below the 65 line-scale, as shown in Figure 1. As only the pointer 14 and trip-lever 23 are in front of the line-scale 3, and as these parts are spaced, the signal-means will not obstruct the operator's view of the line-scale. The signal-means is so 70 constructed and located that it permits the em-rack pointer 5 to pass it after operating the signal-actuating member 23. The signal-means is small and of light weight, and it may be carried in the operator's pocket without discomfort. The 75

bell 16 is so secured to the means by which it is connected to the line-scale that it gives off a clear and distinct sound that unfailingly directs the operator's attention to the fact that he is nearing a point where intermediate justification or alinement is required.

The trip-lever 23 swings to the left against the tension of its spring 30 without operating the hammer-lever 19, when engaged by the pointer 5 while the em-rack 2 is being returned to its normal position, in which position thereof the pointer 5 is at the left-hand end of the line-scale 3.

It is to be understood that any suitable means other than the clip, which consists of the base 7 and clamp-member 31, may be employed for supporting the bell or signal 16, the signal sounding or actuating elements 19 and 23 and the pointer 14 at the required point on the line-scale 3. This supporting or attaching means preserves a predetermined distance between the pointer 14 and the signal-actuating member 23, so as to insure the sounding of the signal before the em-rack pointer 5 reaches the second pointer 14 which forms a part of the signal-means.

The signal-means is adapted to be used in connection with a monotype composing or other machine without making any changes or alterations in the machine. The pads 37 space the upper end portion of the base 7 from the face of the line-scale 3, whereby to prevent the marring of the line-scale and whereby to prevent the arm 25 of the trip-lever 23 from contacting with the line-scale and interfering with the free movement of the trip-lever by the pointer 5 and the spring 30.

Having thus described my invention, what I claim is:

1. The combination with the line-scale, em-rack and pointer of a record strip composing machine, said pointer being carried by said rack and moving over said scale as said rack advances, of a signal-means comprising a signal, an actuating member for said signal arranged in the path of travel of said pointer for operation thereby, a second pointer arranged opposite a selected graduation of said scale in advance of said actuating member, and means for preserving a predetermined distance between said second pointer and said actuating member.

2. The combination with the line-scale, em-rack and pointer of a record strip composing machine, said pointer being carried by said rack and moving over said scale as said rack advances, of a signal, an actuating member for said signal, and means supporting said signal below said scale and supporting said actuating member opposite a selected point on said scale in the path of travel of said pointer for operation thereby.

3. The combination with the line-scale, em-rack and pointer of a record strip composing machine, said pointer being carried by said rack and moving over said scale as said rack advances, of a signal, an actuating member for said signal, and means supporting said signal below said scale and supporting said actuating member in the path of travel of said pointer for operation thereby, said means being adapted to be adjusted with relation to said scale to position said actuating member at different points in the length of said scale.

4. The combination with the line-scale, em-rack and pointer of a record strip composing machine, said pointer being carried by said rack and moving from left to right over said scale as said rack advances, of a signal-means comprising a signal, an actuating member for said signal

arranged in the path of travel of said pointer for operation thereby, and means connected to said scale for supporting said signal and actuating member, said signal-means being constructed and located to permit said pointer to pass the same after operating said actuating member.

5. The combination with the line-scale, em-rack and pointer of a record strip composing machine, said pointer being carried by said rack and moving from left to right over said scale as said rack advances, of a signal-means comprising a signal, an actuating member for said signal arranged in the path of travel of said pointer for operation thereby, and means supporting said signal from said scale and adjustable longitudinally of said scale, said signal-means being constructed and located to permit all the graduations of scale to be seen and to permit said pointer to pass said signal-means after operating said actuating member.

6. The combination with the line-scale, em-rack and pointer of a record strip composing machine, said pointer being carried by said rack and moving from left to right over said scale as said rack advances, of a signal-means comprising a signal, an actuating member for said signal arranged in the path of travel of said pointer for operation thereby, and means for supporting said signal and actuating member for adjustment with relation to said scale to effect the operation of said actuating member at any desired point in the length of said scale, said signal-means being constructed and located to permit all the graduations of said scale to be seen and to permit said pointer to pass said signal-means after operating said actuating member.

7. The combination with the line-scale, em-rack and pointer of a record strip composing machine, said pointer being carried by said rack and moving over said scale as said rack advances, of a signal, an actuating member for said signal arranged in the path of travel of said pointer for operation thereby, a second pointer arranged in advance of said actuating member, and means for supporting said signal, actuating member and second pointer from said scale with said pointer in registration with a selected graduation of said scale.

8. The combination with the line-scale, em-rack and pointer of a record strip composing machine, said pointer being carried by said rack and moving from left to right over said scale as said rack advances, of a signal-means comprising a signal, an actuating member for said signal, and a clip having separable jaws detachably engaged with said scale and carrying said signal and actuating member with said actuating member in the path of travel of said pointer for operation thereby, said signal-means being constructed and located to permit said pointer to pass the same after operating said actuating member.

9. The combination with the line-scale, em-rack and pointer of a record strip composing machine, said pointer being carried by said rack and moving over said scale as said rack advances, of a signal, an actuating member for said signal, a second pointer, and a clip detachably engaged with said scale and carrying said signal, actuating member and second pointer, said second pointer registering with a selected graduation of said scale, and said actuating member being arranged on said clip rearwardly of said second pointer and in the path of travel of said first pointer for operation thereby.

10. A signal of the character set forth, com-

- prising a clip adapted to be engaged with a scale, said clip having relatively spaced extensions at its upper end for contact with the face of the scale, lugs on said clip for contact with the lower edge of the scale to position said extensions as low points on the scale during the application of the clip, a bell on said clip below said extension, a hammer-lever on said clip below said extensions, a trip-lever for said hammer-lever adapted to extend into the path of travel of the pointer associated with the scale, a lug on the trip-lever contacting with said hammer-lever, a spring normally holding said trip-lever against movement in one direction with relation to said hammer-lever, a spring for swinging said hammer-lever when tripped against said bell, and a yielding stop between said hammer-lever and bell against which the hammer-lever is normally held by said second spring.
- 10 11. A signal of the character set forth, comprising a clip adapted to be engaged with a scale,

said clip having relatively spaced extensions at its upper end for contact with the face of the scale, lugs on said clip for contact with the lower edge of the scale to position said extension at low points on the scale during the application of the clip, a bell on said clip below said extension, a hammer-lever on said clip below said extensions, a trip-lever for said hammer-lever adapted to extend into the path of travel of the pointer associated with the scale, a lug on the trip-lever contacting with said hammer-lever, a spring normally holding said trip-lever against movement in one direction with relation to said hammer-lever, a spring for swinging said hammer-lever when tripped against said bell, a yielding stop between said hammer-lever and bell against which the hammer-lever is normally held by said second spring, and pads on said extensions adapted to contact with the face of the scale.

LEO A. SCHMITT.
